FRANK G. JOHNSON, OF PORT RICHMOND, NEW YORK.

Letters Patent No. 81,907, dated September 8, 1868.

IMPROVEMENT IN WATCH-REGULATING ADJUSTMENT.

The Schedule referred to in these Letters Patent and making part of the same.

TO ALL WHOM IT MAY CONCERN:

Be it known that I, Dr. FRANK G. JOHNSON, of Port Richmond, in the county of Richmond, and State of New York, have invented a new and useful Improvement in Regulating Watches; and I do hereby declare that the following is a full, clear, and exact description thereof, which will enable those skilled in the art to make and use the same, reference being had to the accompanying drawings, forming part of this specification.

This invention relates to an improvement in watches, whereby the regulating-hand of the watch is so operated that it may be adjusted with the greatest nicety.

And the invention consists in fixing a fine-threaded screw in the watch with a movable grooved nut thereon, which nut, as it is turned on the screw, shall move the regulating-hand, as will be hereinafter more fully described.

Figure 1 is a partial top or plan view of a watch-movement on an enlarged scale, showing the balance-wheel, hair-spring, and the regulating-hand connected with my regulating-screw and nut.

Figure 2 is a vertical section of the same through the line *x x*.

Similar letters of reference indicate corresponding parts.

The difficulty of turning the regulating-hand of a watch, without moving it too much or too little, has probably been experienced by every one who has ever made the attempt.

To render the operation of turning the hand and properly regulating the time-piece perfectly easy and sure, is the object I have in view in this invention.

For this purpose, I fix a fine-threaded screw, *a*, in the movement of the watch, so secured that it shall be stationary, and on the screw I place a grooved nut, *c*, which, by turning or revolving, can be moved back and forth or in either direction on the screw.

d is the regulating-hand.

The outer end of this hand may be flattened, as seen at *e* in fig. 2, so as to fit the groove in the nut, and be held and moved thereby when the nut is turned.

The regulating-hand being placed in this position instead of on the plate *f*, (as is usual,) the running of the watch may be supposed to approximate to correctness, the same as it would if the hand were placed in its usual position on the plate *f*.

In the latter position, it is next to impossible to move the hand at all either way without moving it too much or too little, while with my adjusting-nut and screw the slightest and most delicate movement in either direction may be given to the hand.

The periphery of the nut *C* is corrugated or serrated, for convenience in moving or turning it, while the end of the hand is made to fit the groove, so that there will not be any slack to take up.

Instead of the flattened end, as seen at *e*, there may be a round pin in the end of the hand, so that when the hand stands at an angle with the groove there would be no possibility of its binding.

g is the hair-spring of the watch.

h is the balance-wheel.

I claim as new, and desire to secure by Letters Patent—

The fixed screw-shaft *a*, upon which the grooved nut *c* carrying the end of the regulating-hand *d* is rotated, all arranged and operating as described, for the purpose specified.
